UNITED STATES PATENT OFFICE.

JOSEPH KARAUS, OF ELIZABETH, NEW JERSEY.

PROCESS OF MAKING REEDS.

Application filed November 28, 1919. Serial No. 341,082.

To all whom it may concern:

Be it known that I, JOSEPH KARAUS, citizen of the United States, and resident of Elizabeth, in the county of Union and State 5 of New Jersey, have invented a certain new and useful improvement in Processes of Making Reeds, of which the following is a specification.

This invention relates to reeds for musical 10 instruments and particularly to the process of their manufacture.

The primary objects of my inventions are to produce simple and efficient ways of manufacture by which better results may be obtained 15 not only in respect to cost but also, and not to a small degree, as to precision, and this to such an extent that the hand tuning of the reed-tongues is practically or entirely eliminated or reduced to a minimum.

20 The doing away with as much hand labor as possible and the necessarily required skill, upon which no one may depend when absolute precision and equality of products is to be mainly considered, is another object of 25 my invention.

A further object of my invention is to provide a process or method for producing, with one series of operations, a plurality of ready tuned or nearly ready tuned reed- 30 tongues.

Another object of my invention is to provide an improved and extremely simple, perfect and inexpensive way of fastening the reed-tongues either singly or in numbers at 35 one operation to the reed-plates.

I am aware of the numbers of patents relating to reeds in general which disclose different ways of manufacture and construction, and I am particularly referring to the 40 kind showing an attachment of reed-tongues to the reed-plates, where portions of the reed-plate material are forced out and where the already prepared reed tongue, having been previously provided with apertures for 45 receiving the forced-out reed-plate extensions, is set upon and attached to these extensions, and I hereby disclaim same. My method is entirely different from the aforesaid kind inasmuch as I use the forced-out 50 reed-plate material to serve not only in place of rivets, but also, and in a primary way, for piercing the reed-tongue and punching thereout pieces corresponding exactly to the shape of the forced-out reed-plate extensions, which latter at the same time replace 55

the punched out portions of the reed-tongue, whereafter their protruding ends are spread to form a head for preventing the tongues from voluntarily disengaging themselves from the plate. 60

The obvious advantages of applying my improved way of fastening the reed-tongues to the reed-plate, is that there is no possible way of the reed-tongues becoming loose or rattling, unless forcibly handled, and there 65 is no necessity for securing the tongues with more than one single rivet. In order to make doubly sure that my piercing reed-plate extension is immovable, I have given same a square shape, although I shall not 70 limit myself to this exact form. The latter may be altered in any convenient way. Such non-shifting extensions come particularly into use for attaching single-blade reed-tongues. When interconnected reed-tongues 75 are to be fastened to reed-plates, round or cylindrical extensions may be readily applied with advantage.

As has been said previously a very important object of my invention is the method 80 of producing a ready tuned or nearly ready tuned set of reed-tongues with one series of operations, with the elimination or reduction to a minimum of hand labor.

In the manufacture of reed instruments, 85 the greatest drawback in this industry was and still is the dependency upon human skill in tuning the reeds to the exact pitch. This may be well and good where the cost does not enter as a primary consideration, and 90 where ample time is allowed for this very important operation. However, even if such conditions prevail, it will hardly be possible to obtain satisfactory results as to quality in harmony and pitch produced in a 95 number of like instruments of the same size, shape and make and serving the same purpose. The only way to make with reasonable accuracy and with the least expenditure of and dependency upon ever-failing 100 human efforts is to produce the reed-plate in a purely mechanical way.

The foregoing and other objects will be more explicitly evident from the following description and the accompanying drawings, 105 forming part of this specification. The drawings illustrate specific forms and mechanisms which serve expressly and purely for explanatory purposes and to which I do not propose to be limited, nor is my process 110

to be confined. On the contrary, there is a possibility of using and constructing numbers of different devices with which identical results may be produced. However, there is absolutely no necessity for any specific mechanism, except a set of hand tools, to accomplish what I claim to be my improved method or process.

Referring to the drawings:

Figure 1 represents three views of a reed-tongue blank.

Figure 2 represents three views of a temporarily bent reed-tongue blank.

Figure 3 is a top view of reed-tongue blank provided with a concave sloping recess.

Figs. 4 and 5 are enlarged transverse sections of Fig. 3, illustrating that the material of the reed tongue is cut away to provide a sloping recess, Figure 4 being an enlarged cross section of Figure 3, looking from the left at section 4-4, while Figure 5 is an enlarged sectional view of Figure 3, looking from the right at section 5-5.

Figure 6 is an enlarged longitudinal sectional view through the recessed blank taken on line 6-6 of Figure 5.

Figure 7 represents an interconnected set of reed-tongues cut out from the blank.

Figure 8 represents individual reed-tongues cut out from the blank.

Figure 9 represents a reed-plate.

Figure 10 represents a complete reed, one half being equipped with interconnected reed-tongues, the other half with individual reed-tongues.

Figures 11, 12, and 13 represent one of the many possible devices for bending and recessing the reed tongue blank.

Figures 14, 15 and 16 illustrate tools for and different operations of fastening the reed-tongues to the reed-plates.

In the figures, 10 designates the straight reed-tongue blank which is made of resilient material, preferably spring-brass strips. The blanked out strip is bent in the way indicated at 11 in Figures 2 and 11. The bent blank 11 is curved transversely and over its entire length, taking a generally convex shape, and preferably forming, when thus curved, a portion of a cylinder. At times it may be preferred however, that the plate be curved to correspond in shape to a part of a cone, or to receive an elliptical, parabolical, hyperbolical, spherical or other curvature, as will be explained later.

The curved blank is held in its bent position, whichever it may be, and subjected to a straight cutting or milling operation at substantially its center portion and over its entire length, leaving at both longitudinal sides edges or ridges 12 and 13 of the original thickness of the strip.

When brought into its original flat position, the plate will have a sloping concave depression or recess 14. In Figures 11 and 12, I have

indicated in a semi-diagrammatical way, an appropriate fixture for obtaining the results sought. A cylindrically shaped steel form 15 is provided with an inclined face, and a form with its face uppermost fastened to a base 16 so that its cylindrical surface is on an incline. The strip 10, indicated in dashed and dotted lines, is then curved and snugly attached to the form 15 by any convenient device in the manner indicated by the arrows I, and receives the shape of the form. A milling cutter 17 or any other instrument begins its cutting operation upon the strip at its lower end 18 and travels in a horizontal plane and in the direction of arrow II until it reached the opposite or the higher end 19 of the plate. Thus a wedge-shaped cut is made on the dashed line 20 and the curved portion of the convex plate is cut off on a plane. Then the plate is released and it snaps into its original straight position as has been said previously, and the formerly straight cut surface forms a concave, sloping recess. The gradually changing shape of the strip may be readily observed at Figure 6. The elevated untouched sides 12 and 13 of the recessed strip may be made parallel, however their shape may vary, as for instance as indicated in Figure 3 in dashed and dotted lines, if it is necessary to widen the recess at one end and make it narrower at the other.

The form upon which the strip is milled may also take different shapes as is shown in Figure 13, where the far end 22 of the form 100 is curved sharper than the near or lower end 23.

The identical or even better results may be obtained by using a less resilient or non-resilient material and stamping or compressing it in such a way as to form the desired shaped depression or recess, leaving the sides at their original thickness. As is well known the compressing operation will increase the resiliency of an article or give it resiliency where there was none. In graduating the compression force in a non-resilient strip, causing one of its ends to be more compressed and therefore more resilient than the other, the results obtained will suit certain conditions more favorably than by forming concave recesses or depressions by the milling operation.

After the strip has acquired the desired shape, it is ready for another operation, that is for making the reed-tongues therefrom. This may be done again in many different ways, two preferred manners being illustrated in the drawings. Figure 7 shows interconnected reed-tongues stamped out at 125 required length from a prepared strip 24, indicated in dashed and dotted lines.

The ridge 12' now serves as interconnection between the individual tongues, ridge 13' being left in parts connected with the 130

tongues to increase their weight and consequently lower their tones. Thus the tongue 25 possesses the longest piece 26 of ridge 13', and gives the lowest tone. Tongue 27 5 possesses a shorter piece 28 of ridge 13' and vibrates quicker, giving a higher tone, and so on until the last tongue 29, which is cut out of the thinner end of the strip 24, is provided with no weight at all and, having 10 been severed at substantially the center line of the strip, possesses a blade-like end, and gives the highest tone of all the tongues stamped out from strip 24.

Similarly Figure 8 shows a number of 15 reed-tongues 25' 27' up to 29' punched out from a prepared strip 24', with the exception that each tongue forms a unit of its own. These are used in instruments where an individual reed is desired, although they 20 may be applied and attached in the same way and at one operation to a similar reed-plate as are the interconnected reed-tongues.

In Figure 9 is shown a reed-plate 30 provided with slots 31 corresponding in size to 25 the respective reed-tongues fitting into the slots.

As may be seen in Figure 10 the interconnected reed-tongues are attached to the reed-plate by round rivets 32 while the individually attached tongues have square projections 33, for preventing them from turning while being proof-tuned or otherwise manipulated with.

The way the reed-tongues are fastened to 35 the plates is illustrated in Figures 14, 15, and 16.

The reed-tongues 125 are placed above a matrix 34 of die 35, on top of the tongues is placed the reed-plate 30, while the upper 40 male die 36 is in elevated position and the counter die 37 is at its lowest stop. Then the male die, which is about as high as half of the thickness of the reed-plate, is pressed down and causes the pressing out of a corresponding portion 38, of the reed-plate 30, which portion pierces and cuts out a corresponding portion 39 of the tongue 125. The plate portion 38 replaces the tongue portion 39 and protrudes after the afore-mentioned 45 operation beyond the tongue 125. The counter die 37 is then elevated and presses against the partially driven out plate portion 38 while the male die 36 is still in its place. After the entire reed-plate, with the male 50 die therein, has been lifted sufficiently to clear the matrix 34, the male die is stopped, while the counter die still travels upward and spreads the protruding end of the partially driven out plate portion 38, as indicated in Figure 16.

As has been said previously, the different steps of the described successive operations do not require and do not depend upon any special mechanism and may be readily accomplished with a set of hand tools, and

these operations together with the produced articles are adapted purely to the manufacture of reeds for musical instruments.

Having thus described my invention, I claim:

1. The process of producing reeds which comprises compressing a reed-tongue strip to form an inclined recess at substantially its center portion and over its entire length, forming tongues of various shape and 75 length from the recessed strip, and fastening them to a reed-plate.

2. The process of producing reeds which comprises compressing the longitudinal center portion of a reed-tongue strip to form 80 elevated side ridges and inclined recess therebetween, forming from the thus prepared strip reed-tongues of various shape and size corresponding to various tones, and nonturnably fastening them to a reed- 85 plate.

3. The process of producing reeds which comprises compressing portions of a non-resilient strip to form longitudinal recesses 90 over its entire length at substantially its center portion, forming resilient reed-tongues from said compressed strip and attaching them to a reed-plate as set forth in the previous claims.

4. The process of producing reeds which comprises compressing the longitudinal center portion of a non-resilient strip, leaving its sides elevated, to form a sloping recess between said elevated sides, forming resilient reed-tongues from the recessed strip 100 and attaching them to a reed-plate as set forth in the previous claims.

5. The process of producing reeds, which consists in transversely bending a resilient flat metal strip throughout its length, recessing it longitudinally along its center portion while in the bent state, the axis of the recess so formed being at an acute angle to the axis or edge of the strip, then releasing the strip from its bent form, and finally cutting the strip into reeds.

6. The process of producing reeds, which consists in transversely bending a resilient flat metal strip throughout its length, recessing it longitudinally along its center 115 portion while in the bent state, the axis of the recess so formed being at an acute angle to the axis or edge of the strip, then releasing the strip from its bent form, and finally cutting a series of reeds therefrom of different sizes.

7. The process of producing reeds, which consists in transversely bending a resilient flat metal strip throughout its length, recessing it longitudinally along its center portion while in the bent state, the axis of the recess so formed being at an acute angle to the axis or edge of the strip, then releasing the strip from its bent form, and finally cutting a series of reeds therefrom 125 130

of different sizes, all the reeds being supported and spaced by a common connection.

8. The process of producing reeds, which consists in transversely bending a resilient flat metal strip throughout its length, recessing it longitudinally along its center portion while in the bent state, the axis of the recess so formed being at an acute angle to the axis or edge of the strip, then releasing the strip from its bent form, and finally cutting a series of reeds therefrom of different sizes, all the reeds being supported and spaced by a common connection, comprising one edge of the strip.

15 9. The process of producing reeds, which consists in transversely bending a resilient flat metal strip throughout its length, recessing it longitudinally along its center portion while in the bent state, the axis of the recess so formed being at an acute angle to the axis or edge of the strip, then releasing the strip from its bent form, and finally cutting a series of reeds therefrom of different weights to vibrate corresponding to

25 musical tones.

10. The herein described process of producing reeds which consists in forming a

longitudinal recess in a metal strip, the axis of the recess being at an acute angle to the axis or edge of the strip, then cutting reeds 30 of various sizes therefrom and finally securing the reeds to a reed plate.

11. The herein described process of producing reeds which consists in forming a longitudinal recess in a resilient metal strip 35 of uniform thickness, the axis of the recess being at an acute angle to the axis or edge of the strip, then cutting reeds of various sizes therefrom and finally securing the reeds to a reed plate.

12. The herein described process of producing reeds which consists in forming a longitudinal recess in a metal strip of uniform thickness, the recess being of less width than the strip, and approximately 45 centrally disposed therein, the axis of the recess being at an acute angle to the axis or edge of the strip, then cutting reeds of various sizes therefrom and finally securing the reeds to a reed plate.

Signed at New York city, in the county of New York, and State of New York, November, A. D. 1919.

JOSEPH KARAUS.
